UNITED STATES PATENT OFFICE.

CHARLES W. PETERSON, OF DETROIT, MICHIGAN.

ELECTRICAL PHONOGRAPH REPRODUCER AND THE LIKE.

Application filed February 1, 1926. Serial No. 85,326.

My invention relates to means for the elimination of the reproduction of undesirable noises in sound reproducers: such as the scratch of the stylus on phonograph records, scratchy static noises in radio loud speakers, and overtones usually superimposed upon reproduced music due to the natural period of vibration of various members of the reproducers themselves, without hampering or distorting the reproduction of the desired sounds.

A further object of my improvements in electrical phonograph reproducers relates to a means of making the armature and stylus holder extremely light so as to offer practically no inertia resistance to the stylus in exactly following the wavy grooves on the record, and yet stiff enough so as not to bend in transmitting the vibrations from the record and thereby distorting the reproduction.

The novel means by which I accomplish the objects of my invention will be clearly understood from the following description, taken in connection with the accompanying drawings forming part of this specification, with the further understanding that while the drawings show a practical form of my invention, the latter is not confined to any strict conformity with the showing of the drawings, but may be changed and modified, so long as such changes and modifications come within the scope of the appended claims.

In the drawings:—

Figure 1 is a front view of a magneto electric phonograph reproducer containing my improvements.

Figure 2 is an end view of what I call the "deadener" in place around the end of the armature and showing the various zones of vibration.

Figure 3 is a vertical cross section of a three ply "deadener" in place on an armature.

Figure 4 is an end view of a rubber deadener which has threads moulded in it in one direction.

Figure 5 is a longitudinal sectional view of the armature and stylus holder used in the reproducer shown in Fig. 1 showing its novel, unusually light, and inflexible construction.

Referring to Fig. 1; 1 is a case, 2 a permanent magnet, 3 an armature of paramagnetic material, 4 are short air gaps between the armature and the N. and S. poles of the

magnet, 5 is the pivot spring, 6 is a paramagnetic connection between the pivot spring and the permanent magnet, 7 is the stylus holder or needle chuck, 8 is a stylus or needle which follows the wavy grooves of the record, 9 is a coil surrounding the armature, 10 is what I call the "deadener," and 11 shows the direction in which the waves in the record vibrate the stylus and armature.

In Fig. 1, as in any other magneto electric phonograph reproducer, the vibrations of the stylus on the record are transmitted to and vibrate the armature, which lengthens and shortens the air gaps between it and the permanent magnet poles causing an alternating magnetic flux to flow thru the armature and coil, which induces an alternating E. M. F. in the coil in correspondence with the vibrations on the record. The difference between my reproducer, Fig. 1, and those previously known, lies in the "deadener" 10, and in the construction of the armature 3, stylus holder 7, and pivot spring 5.

The purpose of "deadener" 10, Fig. 1, is twofold and may be explained as follows: Without the deadener 10 the armature 3 has a natural period of vibration determined by the weight of the vibrating members and the strength of spring 5. In reproducing selections all of the notes in the record which are of the same pitch as the natural period of the armature will be unduly amplified and hence distorted reproduction results. Also if stylus holder 7 and armature 3 are light enough to vibrate freely at high frequencies, so that the highest musical notes will be reproduced, the "scratch" noise, so common in phonographs, will also be reproduced. By novel construction and careful selection of materials in "deadener" 10, which I place somewhere in the vibrating system, as for instance on the armature right above the stylus holder 7, I overcome both of the difficulties described above.

The action of the deadener whereby it accomplishes these results is quite complicated but may be explained as follows: Let us imagine the deadener being a chunk of rubber of the approximate shape shown in Figs. 1 and 2. In accomplishing the first result,—i. e., that of destroying natural periods of vibration of the armature system, the rubber acts as a dead weight hung on the vibrating system and kills the former

natural period due to the change in weight. A new natural period of vibration is not formed because the weight added in the form of rubber has no definite value, but varies for each different frequency, as can be explained by reference to Fig. 2. When armature 3 is being vibrated at a high frequency, deadener 10 offers considerable inertia to being vibrated as a whole, and 10 because of the elastic nature of the rubber, a balance between elastic force and inertia is reached by the vibrations only traveling out as far as, for instance, dotted circle (a) in the rubber. Hence at this frequency, 15 only the weight of rubber out as far as circle (a) is added to the vibrating system.

At a much lower frequency the weight of rubber out of circle (c) may be added to the vibrating system. To obtain a harmful 20 natural period in the vibrating system we must have both a definite strength of spring and a definite weight vibrated at all frequencies.

The same rubber deadener accomplishes 25 the second result, that of preventing the reproduction of the "record scratch", as follows:—"Record scratch" is a jumble of different frequencies, all practically above 3,000 cycles per second. The highest notes 30 we have to reproduce, to give full character to reproductions is 3,000 or so cycles per second. From this it can be seen that if we can find some way of preventing the armature from being vibrated at frequencies 35 above 3,000 but not hinder its vibration below 3,000 we will be able to prevent the reproduction of the scratch and not harm the reproduction of the music. A "deadener" of rubber, when placed as I have shown it, 40 produces just this effect to a remarkable degree, due to the fact that rubber loses most of its elastic properties when subject to vibrations over 3,000 per second, and acts as a rigid body preventing most movements of 45 the armature of over 3,000 cycles per second. This property of rubber may be likened to the well known property of paving pitch,—that when a chunk of pitch is hit a sudden rap with a hammer, it acts as a brittle solid 50 and flies to pieces like glass. The same chunk though, if acted upon by a slow force, may be bent into any shape desired and acts more like a semiliquid than a solid. A "deadener" of this same action may be used 55 in radio "loud speakers" to help prevent the reproduction of "scratchy" sounding atmospheric "static" noises without hindering the reproduction of the musical tones.

Making the deadener out of elastic material and of large diameter as shown in the figures has two more advantages besides those already mentioned: First, to reproduce correctly the desired high musical notes the vibrating system must be as light 60 as possible. My "deadener" does not hang

any excess weight on the vibrating members at high frequencies as the vibrations only affect the deadener inside of zone (a) Fig. 2, for instance. To reproduce low notes correctly, the vibrating system must be very 70 limber. My elastic "deadener" of large diameter as shown in Fig. 2, offers very little resistance to movements of armature 3 at low frequencies, as the full elastic value of the whole deadener comes into play and 75 allows vibration even outside of zone (c). A confined deadener of small diameter has the effect of preventing the reproduction of low notes, but does not hinder the reproduction of high notes and hence causes distortion. 80

Other materials besides rubber make good "deadeners". Soft leather, felt, felts or cloths soaked with liquids, liquids held in a container around the armature, etc., may 85 be mentioned. Sometimes an advantageous result can be obtained by making the deadener out of several materials. For instance, Fig. 3 shows in cross section a deadener made out of a layer of rubber 13, a layer 90 of felt 14, and another layer of rubber 15. Fig. 4 shows one of the best deadener constructions, which is rubber with threads 16 moulded into it with threads in one direction. This deadener is elastic in directions 95 11 and relatively inelastic in directions 12 and prevents any vibrations of the armature in other directions than the correct plane of vibration 11. This adds to purity 100 of reproduction and, in reproducers built like Fig. 1, adds strength so that if the reproducer is dropped on a record the armature 3 or spring 5 will not be damaged.

My novel construction of the armature and stylus holder is shown in the longitudinal cross sectional view Fig. 5. In this armature and stylus holder the two things sought for were extreme lightness and extreme rigidity. The lightness is necessary in order that the stylus may accurately follow the wavy record groove no matter what the frequency, and the rigidity is required in order that there will be no bending of the armature under the stress of vibration, which would produce undesirable overtones 110 in the reproduction.

Making the armature of tubular section fulfills both of these requirements. My novel stylus holder, which is a chuck, is also 115 several times lighter than the conventional set screw type. I make the armature, stylus holder and pivot spring all out of one piece of iron as is seen in Fig. 5. The armature is bored hollow, as 17, from the upper end, leaving a very thin wall 18. The chuck end 120 is then threaded, as shown at 20, and bored at 19 to fit the needle. A slot 21 cut thru the end makes the chuck flexible so that it can contract and clamp the needle when 125 chuck nut 7 is screwed up tight. Lastly 130

the upper end of armature tube 18 is collapsed flat and forms fulcrum spring 5. This spring is thin and wide and allows vibration of the armature only in a direction at right angles to its plane, and also is strong enough to hold the armature away from touching either the N. or S. pole of magnet 2, Fig. 1.

Having thus described my invention, 10 what I claim as new and wish to protect by Letters Patent is:

1. In a sound converting apparatus, a dampening member with threads, or the like, running thru it in one direction making it more elastic in one direction than the other.

2. In a magneto electric phonograph reproducer, an armature, pivoting spring, and stylus holder tube all made out of one piece 20 of paramagnetic metal.

3. In a magneto electric phonograph reproducer, an armature of hollow tubular form and a pivoting spring made by collapsing flat, part of the same tube.

25 4. In a phonograph reproducer, a hollow tubular stylus bar, a rubber deadener mounted thereon, and a contracting jaw stylus chuck connected thereto.

5. In a magneto electric phonograph reproducer, a permanent magnet terminating 30

in N. and S. poles, an armature of paramagnetic material swinging between said poles, with a pivoting spring at one end connecting it with the neutral portion of the magnet and a stylus holder at its other end, 35 an armature coil around said armature, and a deadener in contact with said armature.

6. In a magneto electric phonograph reproducer, the combination of a permanent magnet terminating in N. and S. poles, a 40 hollow tubular armature of paramagnetic material swinging between said poles with a pivoting spring at one end connecting it with the neutral portion of the magnet and a contracting chuck stylus holder at its 45 other end, an armature coil around said armature, and a damping member on said armature above said chuck.

7. In a magneto-electric phonograph reproducer, a permanent magnet terminating 50 in N. and S. poles, an armature of paramagnetic material movable with relation to the magnet poles and having a paramagnetic connection at one end of the armature, with the magnet at the neutral portion thereof, a 55 stylus holder at the other end of the armature, an armature coil about said armature, and a deadener in contact with said armature.

CHARLES W. PETERSON.
